1,988,835

PROCESS FOR BREAKING PETROLEUM
EMULSIONS

Melvin De Groote, St. Louis, and Arthur F. Wirtel, Richmond Heights, Mo., assignors to Tretolite Company, Webster Groves, Mo., a corporation of Missouri

No Drawing. Application March 15, 1934,
Serial No. 715,772

9 Claims. (Cl. 196—4)

This invention relates to the treatment of emulsions of mineral oil and water, such as petroleum emulsions, for the purpose of separating the oil from the water.

- 5 Petroleum emulsions are of the water-in-oil type, and comprise fine droplets of naturally-occurring waters or brines, dispersed in a more or less permanent state throughout the oil which constitutes the continuous phase of the emulsion.
- 10 They are obtained from producing wells and from the bottom of oil storage tanks, and are commonly referred to as "cut oil", "roily oil", "emulsified oil", and "bottom settling".

- 15 The object of our invention is to provide a novel and inexpensive process for separating emulsions of the character referred to into their component parts of oil and water or brine.

- 20 Briefly described, our process consists in subjecting a petroleum emulsion of the water-in-oil type, to the action of a treating agent or demulsifying agent of the kind hereinafter described, thereby causing the emulsion to break down and separate into its component parts of oil and water or brine, when the emulsion is permitted to remain in a quiescent state or subjected to other 25 equivalent separatory procedure.

- 25 The treating agent or demulsifying agent used in our process consists of an ester of a fatty acid or modified fatty acid, in which the carboxylic hydrogen has been replaced by a sulfonated aliphatic residue. Fatty acids are well known demulsifying agents for water-in-oil emulsions, and are disclosed in U. S. Patent No. 1,223,659, dated April 24, 1917, to William S. Barnickel. Likewise, modified fatty acids or their salts or esters are well known demulsifying agents for water-in-oil emulsions, and are disclosed in U. S. Patent No. 1,467,331, dated September 11, 1923, to William S. Barnickel. From the standpoint of said U. S. 30 Patent No. 1,467,331, the acidic hydrogen of the modified fatty acid carboxyl may be replaced by a metal or organic radical, such as a C_3H_5 radical.

- 35 The expression "modified fatty acids" is well understood by those skilled in the art of resolving petroleum emulsions of the water-in-oil type, and has been used frequently in the patent literature to designate a certain well known class of materials. For sake of simplicity and brevity only, the following discussion will consider the 40 carboxy-containing fatty acid as typical of acid, salt and ester. Briefly described, modified fatty acids are modifications of fatty acids obtained by chemical reaction on a fatty acid or its equivalent, so as to result in an addition product or substitution product, and they bear a simple genetic

relationship to each other or to the parent fatty acid or fatty acid compound from which they were derived. Thus, while modified fatty acids do include the salts of modified fatty acids, they do not include salts of unmodified fatty acids, such as soaps, because a salt of a fatty acid is not an addition product. Likewise, it is not a substitution product, because "substitution products" in the sense that such term is used in organic chemistry, is applied not to salts, but to undissociable or indifferent compounds. Furthermore, whereas the acid hydrogen involved in salt formation can be replaced only by metals or metal-like groups, that is, elements or radicals which are electro-positive, substitution may replace the hydrogen of organic compounds by a variety of elements and groups which may be electro-negative. Modified fatty acids retain most of the fundamental characteristics of fatty acids themselves, and are generally characterized by the 15 outstanding identifying property of a fatty acid or fat, i. e., the ability to stain paper so as to leave a translucent spot, at temperatures above the melting point, and to undergo saponification.

20 The treating agent or demulsifying agent contemplated by our process includes esters of a specific kind derived from either fatty acids or modified fatty acids. In order to keep the distinction clear between a fatty acid and a modified fatty acid and yet use a term which will be 25 inclusive of both classes, the expression "fatty acid body" will be herein used to indicate both classes of materials. A fatty acid may be indicated by the formula $R.CO_2H$, in which R is a fatty acid radical such as an oleic acid radical, 30 stearic acid radical, palmitic acid radical, ricinoleic acid radical, and CO_2H indicates the conventional carboxyl radical. If the fatty acid is 35 of the unsaturated type, such as oleic acid, ricinoleic acid, etc., and one produces an addition product by means of a chemical reagent, then the modified fatty acid thus obtained is 40 indicated by the formula $R.XX.CO_2H$, in which XX represents atoms or radicals joined in addition, such as OH , HSO_4 , HSO_3 , Cl , Br , $C_6H_4HSO_3$, etc. XX may represent the same atoms as in 45 the case of oleic acid dichloride, or XX may represent an atom and a radical, as in the case of oleic acid hydrogen hydrogen sulfate. In event that the fatty acid contained more than one 50 ethylene linkage, such as linoleic acid, then one might obtain a modified fatty acid of the type $R.XX.XX.CO_2H$, but this is simply considered as a variety of the $R.XX.CO_2H$ species.

55 Just as the fatty acid of the type $R.CO_2H$

may yield addition products, likewise, it may yield substitution products, and such a modified fatty acid may be designated by the formula R'D.COOH, in which R' is a fatty acid radical such as residue, D is the substituent atom or radical, such as HSO₄, C₆H₄HSO₃, a phthalic acid residue, an oxalic acid residue, an acetic acid residue, a phosphoric acid residue, chlorine, etc., or a residue of the type R''.COO, in which R'' indicates another fatty acid radical residue which may be different, or it may be the same as R', as in the case of poly acids, such as diricinoleic, triricinoleic, etc., and COO is a carboxyl residue.

Fatty acids, such as ricinoleic acid, may yield a modified fatty acid which is both an addition and substitution product. For instance, ricinoleic acid may yield a modified fatty acid which is both an addition and a substitution product and may be indicated by the formula R'D.XX.COOH, in which the various symbols have the same significance as previously. The formula R.COOH includes fatty acids, such as oleic acid, ricinoleic, stearic acid, etc. The formulas R.XX.COOH, R'D.COOH, and R'D.XX.COOH include the conventional modified fatty acids. Fatty acid bodies are selected from the class comprising:

30 R.COOH
R.XX.COOH
R'D.COOH
R'D.XX.COOH,

in which the symbols have their previous significance. The above formulas indicate the simple genetic relationship existing among the members of the class.

The treating agent or demulsifying agent employed in our present process is a sulfo aliphatic ester of a fatty acid body, that is the ester of either a fatty acid or a modified fatty acid, in which a sulfo aromatic residue has replaced the carboxylic hydrogen of the fatty acid or modified fatty acid. The production of such sulfo aliphatic esters may be accomplished in a variety of manners. A number of methods for producing such sulfo aliphatic esters are disclosed in U. S. Patent No. 1,881,172, dated October 4, 1932, to Karl Daimler and Karl Platz. Briefly stated, one method contemplates reacting the reaction product of ethyl alcohol and sulfuric anhydride with a fatty acid at approximately 45° C. and stirring for ten hours, when the mass is introduced into ice water and the whole is then washed with a solution of sodium chloride. On neutralization, a white paste is obtained which dissolves when diluted with water.

The methods disclosed in said U. S. Patent No. 1,881,172 are applied to fatty acids, but it is obvious that they are also applicable to modified fatty acids of the type previously indicated.

60 If a fatty acid is indicated by the formula RCOOH, then the sulfo aliphatic ester may be indicated by the formula R.COO(T.SO₃.Z), in which R has the same meaning as previously indicated, COOH is the carboxyl residue, T is the aliphatic residue, SO₃ is the conventional sulfonic acid residue, and Z represents the hydrogen of the sulfonic acid or its equivalent, such as a metal atom, for example, a sodium or potassium, or else an ammonium radical, basic amine radical, calcium, magnesium, etc., or Z may be an organic radical, such as a C₂H₅ radical. Corresponding to a sulfo aliphatic ester of the fatty acids, one may obtain the sulfo aliphatic esters of the modified fatty acids, and they may be designated by the following type formulas:

5 R.XX.COO(T.SO₃.Z); R'D.COO(T.SO₃.Z), and R'D.XX.COO(T.SO₃.Z), in which the symbols have the same significance as previously. It is to be noted that (T.SO₃.Z) replaces the carboxylic hydrogen in both modified and unmodified fatty acids.

As pointed out in U. S. Patent No. 1,881,172, previously referred to, these reagents have a great wetting power, and thus presumably are colloidal in character, and they are surface active. A great many substances which give colloidal solutions and are hydrophile or lipophile are excellent demulsifying agents for water-in-oil emulsions. However, the list of reagents which are capable of acting as wetting agents, 15 frothing agents, emulsifying agents, etc., has increased to such a marked degree that it includes large classes of materials which are not of any significant value as demulsifying agents.

The treating agent that we prefer to use in 20 practising our process is preferably prepared in the following manner: The dry potassium salt of ricinoleic acid is prepared by saponification of castor oil in the conventional manner. To approximately 436 parts by weight of this salt are 25 added approximately 148 parts by weight of phthalic anhydride and the mixture heated at 140° C. with constant stirring, until the reaction is complete. To this mass approximately 92 parts by weight of glycerol are added and the 30 mass heated with constant stirring at the temperature previously employed until the acidity of the reaction product is substantially nil. The product thus obtained consists principally of a phthalic acid residue, united through one carboxyl with a glycerol residue, and through the other carboxyl with sodium ricinoleate by combination through the alcoholiform hydroxyl of the ricinoleate. This product is agitated vigorously with dilute hydrochloric acid so as to decompose the salt, with the liberation of the free glyceryl phthalyl ricinoleic acid. Care must be taken so as not to decompose the ester. The ester is then freed of excess water and dried over anhydrous sodium sulfate. To this ester is then 40 added approximately 200 parts by weight of ethionic acid (obtained from ethyl alcohol and sulfuric anhydride), at a temperature of approximately 45° C., and the mixture stirred for ten hours. This mixture is then introduced into approximately 300 parts by weight of ice water while stirring and the whole mass is subsequently washed with a solution of sodium chloride. On neutralization a white paste is obtained which 45 dissolves when diluted with water. The reaction probably takes place according to the equation:

55 Another treating agent or demulsifying agent that we may use in practising our process, is prepared as follows: Approximately 436 parts by weight of dry potassium ricinoleate is heated at approximately 140° C., with approximately 148 parts of phthalic anhydride until the reaction is complete. The acid ester is liberated with dilute hydrochloric acid, as in the preceding example. This acid ester is then allowed to react with approximately 400 parts by weight of ethionic acid, prepared as suggested in the previous example, until the reaction is practically complete, where- 60 by most of the ester formed will be found to contain two sulfonic groups, one attached to the 65 70 75

ricinoleic acid group and one to the phthalic acid group. Of course, there will be present some of each of the two mono-sulfonates possible, but the bulk will be the disulfonate.

5 Another treating agent or demulsifying agent that we may use in practising our process can be prepared as follows: To approximately 200 parts by weight of ethionic acid are added, at approximately 45° C., 298 parts by weight of ricinoleic acid. This mixture is stirred until the reaction product gives a clear water solution. This product is then mixed with approximately 400 parts by weight of ice water and approximately 100 parts of a saturated sodium chloride solution is added. On standing, the ricinoleic ester of the hydroxy ethane sulfonic acid is deposited on the bottom. The top layer is withdrawn and the lower layer neutralized as such or washed again with a 20% solution of sodium chloride and then neutralized.

20 Still other treating agents or demulsifying agents capable of use in our process, can be produced by reacting allyl alcohol with potassium acid sulfite and forming the hydroxy propane sulfonic acid salt, and subsequently reacting 120 parts by weight of this salt with 155 parts by weight of castor oil and passing a current of dry hydrochloric acid gas through the mixture. After 24 hours the reaction is complete. This product is soluble in water to a clear solution. The reaction product is purified and finished as in the preceding example.

25 It is understood wherever the replaceable hydrogen is present in the reagent, for instance, the replaceable hydrogen of the carboxyl radical of the phthalic acid residue previously mentioned, that said acid hydrogen may be replaced by any of the customary radicals, such as sodium, potassium, ammonium, basic amine radicals, ethyl radicals, methyl radicals, etc. Reagents thus produced will show the widest variety in their solubility. Some may be water-soluble, some may be oil-soluble, some may be soluble in both water and oil, and some may be substantially insoluble in either oil or water. It appears paradoxical to speak of breaking an oil field emulsion by means of a reagent which is substantially insoluble in either oil or water. On the other hand, it must be remembered that oil field emulsions are frequently broken by the addition of one part of a chemical reagent to 20,000 parts or 30,000 parts of emulsion. Thus, even though a reagent is substantially insoluble in oil and in water, yet it may be sufficiently soluble so that it is entirely dissolved in the minute amount in which it may be used.

30 The specific form, state, or condition of the treating agent at the time it is used or applied to the emulsion to be treated is immaterial and may be varied to suit existing conditions. It can be used in substantially anhydrous state or in solutions of any convenient strength. The treating agent may be diluted with any suitable solvent, such as ethyl alcohol, methyl alcohol, isopropyl alcohol, butyl alcohol, kerosene, or any other hydrocarbon solvent, benzol, xylene, solvent naphtha, carbon tetrachloride, pine oil, etc.

35 The treating agent can be employed either alone or in admixture or combination with other well known treating agents for breaking petroleum emulsions of the water-in-oil type, such as water softeners, modified fatty acids, petroleum sulfonic acids, or their salts, etc.

40 In practising our process, a treating agent or demulsifying agent of the kind above described

is brought in contact with the emulsion to be treated, etc.

Having thus described our invention, what we desire to secure by Letters Patent is:

1. A process for breaking petroleum emulsions of the water-in-oil type, which consists in subjecting the emulsion to the action of a demulsifying agent containing a sulfo-aliphatic ester of a fatty acid of the type $R''\text{COO}(T\text{SO}_3\text{Z})$, in which R'' is a fatty acid radical, COO is a carboxyl residue, T is the aliphatic residue, SO_3 is the conventional sulfonic acid residue, Z represents the acidic hydrogen atom of the sulfonic acid or its equivalent, and $(T\text{SO}_3\text{Z})$ replaces the carboxylic hydrogen. 5

15 2. A process for breaking petroleum emulsions of the water-in-oil type, which consists in subjecting the emulsion to the action of a demulsifying agent containing a sulfo-aliphatic ester of a modified fatty acid of the type 10

20 $R'''\text{COO}(T\text{SO}_3\text{Z})$,

25 in which R''' is a modified fatty acid radical, COO is a carboxyl residue, T is the aliphatic residue, SO_3 is the conventional sulfonic acid residue, Z represents the acidic hydrogen atom of the sulfonic acid or its equivalent, and $(T\text{SO}_3\text{Z})$ replaces the carboxylic hydrogen. 25

30 3. A process for breaking petroleum emulsions of the water-in-oil type, which consists in subjecting the emulsion to the action of a demulsifying agent containing a sulfo-aliphatic ester of a modified fatty acid of the type 30

35 $R'D\text{COO}(T\text{SO}_3\text{Z})$,

40 in which $R'D$ is a modified fatty acid residue of the substituted type, D is a substituent atom or radical attached to R' , COO is a carboxyl residue, T is the aliphatic residue, SO_3 is the conventional sulfonic acid residue, Z represents the acidic hydrogen atom of the sulfonic acid or its equivalent, and $(T\text{SO}_3\text{Z})$ replaces the carboxylic hydrogen. 40

45 4. A process for breaking petroleum emulsions of the water-in-oil type, which consists in subjecting the emulsion to the action of a demulsifying agent containing a sulfo-aliphatic ester of a modified fatty acid of the type 45

50 $R'D\text{COO}(T\text{SO}_3\text{Z})$,

55 in which $R'D$ is a modified fatty acid residue of the substituted type, D is a substituent dibasic carboxy acid residue attached to R' , COO is a carboxyl residue, T is the aliphatic residue, SO_3 is the conventional sulfonic acid residue, Z represents the acidic hydrogen atom of the sulfonic acid or its equivalent, and $(T\text{SO}_3\text{Z})$ replaces the carboxylic hydrogen. 55

60 5. A process for breaking petroleum emulsions of the water-in-oil type, which consists in subjecting the emulsion to the action of a demulsifying agent containing a sulfo-aliphatic ester of a modified fatty acid of the type 60

65 $R'D\text{COO}(T\text{SO}_3\text{Z})$,

70 in which $R'D$ is a modified fatty acid residue of the substituted type, D is a substituent phthalic acid residue attached to R' , COO is a carboxyl residue, T is the aliphatic residue, SO_3 is the conventional sulfonic acid residue, Z represents the acidic hydrogen atom of the sulfonic acid or its equivalent, and $(T\text{SO}_3\text{Z})$ replaces the carboxylic hydrogen. 70

75 6. A process for breaking petroleum emulsions of the water-in-oil type, which consists in sub-

jecting the emulsion to the action of a demulsi-
fying agent containing a sulfo-aliphatic ester
of a modified fatty acid of the type

R'D.COO(T.SO₃.Z),

5 in which R'D is a modified fatty acid residue
of the substituted type, D is a substituent phthalic
acid residue attached to R', COO is a carboxyl
residue, T is an ethane derivative, SO₃ is the
10 conventional sulfonic acid residue, Z represents
the acidic hydrogen atom of the sulfonic acid or its
equivalent, and (T.SO₃.Z) replaces the carboxylic
hydrogen.

7. A process for breaking petroleum emulsions
15 of the water-in-oil type, which consists in sub-
jecting the emulsion to the action of a demulsi-
fying agent containing a sulfo-aliphatic ester of
a modified fatty acid of the type

R'D.COO(T.SO₃.Z),

20 in which R'D is a modified fatty acid radical of

the substituted type, D is a substituent phthalic
acid residue attached to R', COO is a carboxyl
residue, T is an ethane derivative, SO₃ is the
conventional sulfonic acid residue, Z represents
a metal atom, and (T.SO₃.Z) replaces the car-
boxylic hydrogen.

8. A process for breaking petroleum emulsions
of the water-in-oil type, which consists in sub-
jecting the emulsion to the action of a demulsi-
fying agent containing the hydroxy ethane sul-
10 fonic ester of phthalyl ricinoleic acid in the form
of a water-soluble salt.

9. A process for breaking petroleum emulsions
of the water-in-oil type, which consists in sub-
jecting the emulsion to the action of a demulsi-
fying agent containing the hydroxy ethane sul-
15 fonic ester of phthalyl ricinoleic acid in the form
of a water-soluble ammonium salt.
